TELEPHONE BASE

Thomas G. Cannon, Lockport, Ill., assignor to Automatic Electric Laboratories, Inc., Northlake, Ill., a corporation of Delaware

Filed June 23, 1960, Ser. No. 61,092

Term of patent 14 years

FIG. 1

FIG. 2

Fig. 1 is a front perspective view of a telephone base showing my new design and having a handset shown thereon in broken lines for purposes of illustration only; and

Fig. 2 is a perspective view from the rear, of the telephone base.

I claim:

The ornamental design for a telephone base, substantially as shown and described.
